UNITED STATES PATENT OFFICE.

FRIEDRICH NELLEN AND ALBERT VOIGT, OF ESSEN, GERMANY.

PROP FOR MINES.

No. 881,609.

Specification of Letters Patent. Patented March 10, 1908.

Application filed November 6, 1907. Serial No. 400,973.

To all whom it may concern:

Be it known that we, FRIEDRICH NELLEN and ALBERT VOIGT, subjects of the German Emperor, residing at Essen, Germany, have invented certain new and useful Improvements in Props for Mines, of which the following is a specification.

The present invention relates to props for mines which are made from artificial stone instead of being from wood or iron as usual. The improved props are very cheap and of great durability.

In the accompanying drawings the improved prop for mines is shown by way of example.

Figures 1 and 2 represent in vertical section two forms of the prop. Fig. 3 is another modification shown in vertical section. Fig. 4 is a detail view of the valve used in Fig. 2, which is represented on a larger scale. Fig. 5 is a section on line $x-x$ of Fig. 2.

The improved prop shown in Fig. 1 consists of a hollow cylinder a which is closed at its lower end through a bottom k having an upper edge of coneshaped cross section, engaging with the beveled surface of the bottom end of the cylinder. The hollow cylinder a and the bottom piece k are made from tufaceous limestone or other suitable waste stone which is brought into proper shape by compression. The cylinder is covered with a casing b made from any suitable waste material, such as shavings for example.

The cylinder with its shell are manufactured in the following manner:—The cylinder a and its bottom piece k are made separately from pulverized waste stone which is suitably moistened and brought into proper shape by pressure. The shavings for the cover are stuck together with the ends and wound around the cylinder which, after the bottom piece has been put in place, is placed on a spindle. The cover of shavings is made of the required thickness and then impregnated with a suitable substance to render it proof against fire and rot. The shavings are pressed on the cylinder by means of a pressing roller. The cover can be made of any other suitable material, such as paper and the like. The inner wall of the cylinder is smooth. The cylinder is filled with gravel

or waste stone and a piston c is placed upon the filling of the cylinder which is made from the same material as the cylinder and covered in a similar manner with a cover d and 55 which has a large head. The pressure of the ground when the prop is used gradually compresses the filling f of the prop. Owing to the gradual increase of the pressure exerted on the prop the breaking of the same is prevented.

According to Fig. 2 the cylinder is not filled with waste stone. The piston c is raised up to the hanging-wall of the lode by means of air under pressure which is supplied 65 to the cylinder through a valve g (preferably a non-return valve). This valve is fixed in the bottom end of the cylinder by means of a nut h . A washer i at the lower end of the piston serves for securing the packing of the 70 piston. When the piston is sufficiently pressed against the hanging-wall, the valve g is automatically closed through the pressure exerted by the piston.

According to Fig. 3 the prop consists of a 75 solid cylinder c with cover d , the piston being dispensed with. The dimensions of the cylinder and the piston can be varied according to requirement.

What we claim as our invention and desire to secure by Letters Patent is:—

An improved prop for mines comprising in combination a hollow cylinder closed at the bottom and made from pressed waste stone, a cover for said cylinder made from impregnated shaving, a piston in said cylinder made from pressed waste stone and provided with a cover made from shavings, and a suitable filling of the cylinder adapted to be compressed by the pressure exerted upon the piston by the hanging-wall of the lode, substantially as described and shown and for the purpose set forth.

In testimony whereof we have hereunto set our hands in presence of two subscribing 95 witnesses.

FRIEDRICH NELLEN,
ALBERT VOIGT.
